(57) **CLAIM**

The ornamental design for a steering wheel spinner, as shown and described.

DESCRIPTION

FIG. 1 is a perspective top front right view of a steering wheel spinner, showing my new design;

FIG. 2 is a front elevation view thereof, wherein a rear elevation view is an identical image thereof;

FIG. 3 is a right elevation view thereof, wherein a left elevation view is an identical image thereof;

FIG. 4 is a top plan view thereof; and,

FIG. 5 is a bottom plan view thereof.

1 Claim, 4 Drawing Sheets(56)
